UNITED STATES PATENT OFFICE

OSCAR C. SCHMIDT, OF CINCINNATI, OHIO, ASSIGNOR TO THE CINCINNATI BUTCHERS' SUPPLY COMPANY, OF CINCINNATI, OHIO, A CORPORATION OF OHIO

FLOOR DRAIN

Application filed September 28, 1931. Serial No. 565,585.

My invention relates to floor drains such as are used in slaughter houses, as in the bleeding floor or so-called bleeding pan, for receiving the blood drained from the slaughtered animal.

The floor of a bleeding floor or bleeding pan slopes toward an opening, through which the blood is received for being collected, for instance, in a reservoir or tank, for conservation and treatment for consumption as stock food, and for other purposes. It is desirable that equipment of this nature shall be sanitary and capable of being readily cleaned.

It is the object of my invention to provide an improved floor drain having a passage through which the blood is arranged to pass, and a passage through which cleansing fluid is arranged to pass, with valve mechanism so arranged that when one passage is opened the other is automatically closed; further, to provide such passages with venting means for venting deleterious odors; further, to provide an inlet opening for such passage, and a trap between said inlet opening and said passage; and further, to provide novel operating means for the valves.

My invention will be further readily understood from the following description and claims, and from the drawings, in which latter:

Fig. 1 is a side elevation of my improved device, mounted in a bleeding floor shown in vertical section on the line 1—1 of Fig. 2, and exemplifying connections for its passages.

Fig. 2 is an end view of the same, partly in section on the line 2—2 of Fig. 1, and partly broken away.

Fig. 3 is a plan view of my improved device, with the bleeding floor partly broken away, and the handle in one position of use.

Fig. 4 is a similar view, partly broken away, with the handle in its reverse position of use.

Fig. 5 is a vertical section of my improved device, taken on the line 5—5 of Fig. 3.

Fig. 6 is a vertical section of the same, taken in the plane of the line 6—6 of Fig. 5.

Fig. 7 is a horizontal section of the same,

taken in the plane of the irregular line 7—7 of Fig. 5; and,

Figs. 8 and 9 are cross-sectional detail views taken respectively on the lines 8—8 and 9—9 of Fig. 5.

The bleeding floor is exemplified at 11. In usual practice the slaughtered animal is suspended above the bleeding floor and its blood drained onto the bleeding floor. The bleeding floor slopes toward my improved device 60 which is arranged to receive blood thus drained.

My improved device preferably comprises a casing 12 exemplified as a casting. It comprises an inlet compartment 13 and an outlet 65 compartment 14, having a closed wall 15 therebetween, which with a wall 16 forms a trap 17 between the compartments.

An outer wall 18 surrounds the compartments. The casing has a top plate 19 in 70 which there are openings 20, 21. The top plate has an inwardly and downwardly sloping peripheral flange 22, the outer margin of which merges with the upper draining surface 23 of the bleeding floor.

A grating 25 closes the opening 20, being received in a rabbet 26 in the upper end of the margin of the wall of said opening. The grating has openings 27 permitting flow of the fluid through the grating but arresting 80 solid particles. It is secured in place by screws 28.

The opening 21 is closed by a sealing plate 31, secured in a rabbet 32 in the upper end of the wall of said opening, as by screws 33, and 85 having a gasket 34 between it and the lower wall of said rabbet.

A service passage 35 communicates with the outlet compartment 14 and a refuse passage 36 also communicates with this outlet 90 compartment. The outlet compartment is shown provided with a floor 37 which is higher than the floor 38 of the trap 17. The ports or openings 39, 40, for said passages are shown in this floor.

Valves 45, 46, are provided for the respective passages, the passages being provided with valve seats 47, 48, for said valves. These valves are preferably heavy valves, made for instance of metal, so that they will 100

readily close said passages when they descend upon the same. The valve seats and valves are shown of frusto-conical form and of substantial length.

5 A rocker frame 51 is in the outlet compartment and is provided with arms 52, 53, having hooks 54, 55, for receiving rings 56, 57, on the valves. The rocker frame comprises a rock shaft 58 pivoted in bearings 59, 60, 70 in the casing, the casing having a hole 61 through which a tool for finishing the bearings may be received, the hole being sealed by a plug 62 threaded therein.

15 An operating rock shaft 65 is pivoted in bearings 66, 67, in the walls of the inlet compartment, the outer wall of this compartment being provided with a hole 68 through which a suitable tool for finishing said bearings may be received, the hole being sealed 80 when the device is in use by a threaded plug 69.

25 A yoke 71 has hubs 72, 73, about the respective rock shafts 65, 58, fixed thereto, as by set screws 74, 75. The rock shafts are shown square in cross section, and the openings therefor in the hubs 72, 73, are shown rectangular in cross section and open at their 85 ends for readily locating the hubs and for readily causing the hubs and shafts to move together.

30 The arms 52, 53, are extended in opposite directions and have a hub 76 between them, which is provided with a rectangular slot 77 having outward opening and arranged to fit 90 over the rock shaft 58 for being readily received over the rock shaft and held in place thereon by a set screw 78.

35 The bearings 59, 60 and 66, 67 are also 95 preferably provided with upwardly extending openings so as to permit the pivot ends of the rock shafts to be readily received therein. The walls of the holes in the hubs 72, 73 of the yoke frame are shown rectangular and with laterally extending openings so that the 100 bearings may be slipped over the rock shafts 65, 58 by movement in a direction crosswise of the yoke frame for readily assembling the yoke frame on the rock shafts. The set screws 74, 75, are in the side walls of the slots 105 formed in said hubs. The set screw 78 is also in the side wall of the hub 76 in the rocker frame 51.

40 The bow-end of the yoke extends below the wall 15 of the trap 17. The yoke frame also 110 has an upwardly extending operating arm 81. A handle 82 has pivotal connection with the upper end of this arm. The arm extends through a slot 84 in the grating, and the operating handle normally lies flat with the 115 top wall of the casing, being received in a recess 85 therein. This recess is shown partly in the grating plate and partly in the web 86 of the top wall of the casing.

45 The pivotal connection between the handle and the operating arm is by means

of a pivot screw 87. The handle is shown of loop form having an opening 88 through which the fingers or a tool may be readily inserted for raising the handle. Pivot bearings 89, 90, are at the end of the loop and in line with a pivot bearing 91 at the upper end of the operating arm, the pivot screw being received through said bearings and having a threaded connection with one of the end 120 bearings.

When the handle is located in the recess 85, one of the valves is in seated relation and the handle is in locked relation to prevent unseating of the valve. When the other valve is to be seated the handle is raised on its pivot and the operating arm swung in its slot toward the other end of the slot, the handle being reversed and again let into its recess for positioning the other valve in closed relation and locking the handle in its position. The swinging end of the handle is held in locked relation between end walls 92, 93, of the recess 85.

50 The handle is provided with indicia on its reverse sides to indicate the valve which is open when a given side of the handle is uppermost. Thus the handle is provided with the word "blood" at 94 on one side to indicate that when this side is uppermost the blood passage is open, and with the word "sewer" at 95 on its other side to indicate that when this side is uppermost or in view the refuse valve, or valve to the sewer, is open and the other valve is closed.

55 The valves are preferably heavy plug valves 100 whose connections with their operating means are releasable.

60 The passage 35 is the service passage for receiving the liquid to be preserved. A pipe 97 connects with this passage and leads to a suitable tank 98, the passage 36 is the refuse passage and arranged to receive the water and ingredients when washing and flushing the 105 bleeding floor. A suitable pipe 99 connects with this passage and leads, for instance, to the sewer.

65 A vent passage 101 is provided, shown connected by branches 102, 103, respectively with the service passage 35 and the refuse passage 36. A pipe 104 is shown connected with the 110 vent passage, and leads to a suitable exhaust system or through the roof of the building.

70 The vent passage and its branches are shown as part of the casting of the casing.

75 The casing is provided with a flange 106 115 which is imbedded, for instance, in the concrete of the floor 11.

80 A spring 111 surrounds the rock shaft 65 120 and exerts lateral pressure upon the yoke frame 71 for retarding movement of the yoke frame and holding it in its valve seating positions. It creates friction for instance between the ends of the hub 72 and the bearing 67 when shifting the arm.

85 My improved device forms a simple and 130

effective means for accomplishing the result desired. It is strong and durable and its valves are readily operable and arranged to be readily seated. The perforated plate 25 and the closing plate 31 are readily removable for inspection of the parts, the handle 82 being readily removable from the operating arm 81.

The operating yoke is readily removable from its rock shafts by loosening the screws 74 and 75 and shifting the operating yoke laterally for releasing it from its rock shafts. The rocker arm 51 is readily removable from its rock shaft by loosening the screw 78 and raising the rocker arms from the shaft, and the valves are readily removable from their operating arms by lifting the same therefrom. The rock shafts are also readily raised out of their bearings. The operating mechanism is readily taken apart for cleaning, repairing and attention.

The vent vents each of the passages whether closed or not, and the trap closes each of the passages to the inlet opening. The trap is small in cubic contents but is effective in preventing venting from the respective passages through the inlet opening. The hermetic closing of the outlet compartment compels all matter to pass through the trap before it reaches either of the passages. The location of the operating member for the valves in the trap avoids the necessity of providing any packing or leak proofing for the operating parts of the valve.

The handle when operated for closing either valve is seated in its recess, the end walls of the recess holding the handle endwise for preventing shifting of the operating parts of the valves.

Having thus fully described my invention, what I claim as new, and desire to secure by Letters Patent, is:

1. A floor drain comprising a service passage and a refuse passage, an inlet opening, and a trap between each of said first named passages and said inlet opening.

2. A floor drain comprising a service passage and a refuse passage, an inlet opening, a trap between each of said first named passages and said inlet opening, and a vent passage communicating with both said first named passages.

3. A floor drain comprising an inlet compartment and an outlet compartment, said outlet compartment having a floor above the floor of said inlet compartment, a service opening and a refuse opening in the floor of said outlet compartment, and a closed wall between said compartments extending below the level of said floor of said outlet compartment and a passage between said closed wall and said floor forming a trap between said compartments.

4. A floor drain comprising an inlet compartment and an outlet compartment, said

outlet compartment having a floor above the floor of said inlet compartment, a service opening and a refuse opening in the floor of said outlet compartment, a closed wall between said compartments extending below the level of said floor of said outlet compartment forming a trap between said compartments, and closure means for said respective openings.

5. A floor drain comprising an inlet compartment and an outlet compartment, said outlet compartment having a floor above the floor of said inlet compartment, a service opening and a refuse opening in the floor of said outlet compartment, a closed wall between said compartments extending below the level of said floor of said outlet compartment for forming a trap between said compartments, and a vent communicating with said outlet compartment.

6. A floor drain comprising an inlet compartment, an outlet compartment and a trap between said compartments, a service passage and a refuse passage communicating with said outlet compartment, closure means by said passages, and venting means for said passages.

7. A floor drain comprising an inlet compartment, an outlet compartment and a trap between said compartments, a service passage and a refuse passage communicating with said outlet compartment, closure means by said passages, venting means for said passages, and operating means for said closure means comprising an operating part in said inlet compartment and an operated part in said outlet compartment having operative connections with said closure means.

8. A floor drain comprising an inlet compartment, an outlet compartment and a trap between said compartments, a service passage and a refuse passage communicating with said outlet compartment, closure means by said passages, venting means for said passages, operating means for said closure means comprising an operating part in said inlet compartment and an operated part in said outlet compartment having operative connections with said closure means, said operating means comprising a reversible operating handle, and indicia on the reverse sides of said handle indicating said respective passages.

9. A floor drain comprising an inlet compartment, an outlet compartment and a trap between said compartments, an inflow opening for said inlet compartment, a service passage and a refuse passage opening into said outlet compartment, a valve for each of said passages, a rocker frame having operative connections with said valves operating said valves in reverse directions, a handle for said rocker frame, and locking means locking said handle in positions for closure of each of said valves.

10. A floor drain comprising an inlet com-

partment, an outlet compartment and a trap between said compartments, an inflow opening for said inlet compartment, a service passage and a refuse passage opening into said outlet compartment, a valve for each of said passages, a rocker frame having operative connections with said valves operating said valves in reverse directions, and a sealing cover above said valves for said outlet compartment at one side of said trap.

11. A floor drain comprising an inlet compartment, an outlet compartment and a trap between said compartments, an inflow opening for said inlet compartment, a service passage and a refuse passage opening into said outlet compartment, a valve for each of said passages, and a rocker frame having operative connections with said valves operating said valves in reverse directions, said operating part having a portion in said trap and an operating portion in said inlet compartment.

12. A floor drain comprising an inlet compartment, an outlet compartment and a trap between said compartments, a service passage, a refuse passage, a valve for each of said passages, a rock shaft in each of said compartments, a yoke extending into said trap and having operative connections with said rock shafts, and an operating handle for said yoke at the inlet compartment side of said trap.

13. A floor drain comprising an inlet compartment, an outlet compartment and a trap between said compartments, a service passage and refuse passage communicating with said outlet opening, a valve for each of said passages, a rock shaft in each of said compartments, and a yoke extending into said trap and having releasable connections with said rock shafts and an operating part in said inlet compartment, and said valves having releasable connections with said rock shaft in said outlet compartment.

14. A floor drain comprising an inlet compartment, an outlet compartment and a trap between said compartments, a service passage and a refuse passage communicating with said outlet compartment, a rock shaft in each of said compartments, a rocker arm having releasable connection with said rock shaft in said outlet compartment and releasable operative connections with said valves, and a yoke having a part extending into said trap and having releasable connections with said rock shafts, and said rock shafts having releasable connections with the walls of said respective compartments.

15. A floor drain comprising an inlet compartment, an outlet compartment, a downwardly extending wall and an upwardly extending wall between said compartments forming a trap between said compartments, a service passage and refuse passage communicating with said outlet compartment, a valve for each of said passages, a perforated

closure for said inlet compartment, a sealing closure for said outlet compartment, and a rocker arm for said valves having a portion extending between said walls and through said trap, and operating means outside said inlet compartment for operating said valves.

In testimony whereof, I have hereunto signed my name.

OSCAR C. SCHMIDT.
